UNITED STATES PATENT OFFICE.

HARRY M. DOUBLEDAY, OF COLUMBUS, OHIO.

INCANDESCENT-ELECTRIC-LAMP FIXTURE.

SPECIFICATION forming part of Letters Patent No. 378,358, dated February 21, 1888.

Application filed September 23, 1887. Serial No. 250,513. (No model.)

To all whom it may concern:

Be it known that I, HARRY M. DOUBLEDAY, a citizen of the United States, residing at Columbus, Franklin county, Ohio, have invented 5 new and useful Improvements in Incandescent-Electric-Lamp Fixtures, of which the following is a specification.

My invention relates to improvements in those incandescent-electric-lamp fixtures in 10 which the lamp is suspended by means of the conducting-wires from a ceiling-block; and the objects of my improvements are to provide a ceiling-block consisting of a non-conducting 15 disk having electrical connections and a shell having means of ready attachment to said disk and adapted to support the pendent conducting-wires of the lamp.

In the accompanying drawings, Figure I is an elevation of my device. Fig. II is an axial 20 vertical section in a plane parallel to the elevation. Fig. III is a plan of the disk.

Similar letters refer to similar parts throughout the several views.

A is a non-conducting disk, which has screws 25 a, to which is attached, by means of bayonet-joints b b, the shield B, said shield having secured within its lower orifice, by means of pins c c, a button, C, of wood or other insulating material. This button is flared at its upper 30 end in order to rest upon a shoulder, d, of said shield, thus affording additional strength for the supporting of the conducting-wires E E, which pass through an orifice, D, said con-

ducting-wires being secured, respectively, by the binding-screws e e' to the plates F F'. A 35 safety-catch of a fusible wire, f, connects plate F with F'. Plates F F' F" are rigidly attached to the insulating-disk A by means of screws h. The plates F' F" have binding-screws e" e'', which screws are capable of receiving con- 40 ducting-wires i i.

A ceiling-block such as above described provides a simple and cheap means of suspension of a lamp and contains all the necessary connections, doing away with the usual separable 45 plug and socket.

I am aware that it is not broadly new to fasten the cut-out and other electrical connections to a ceiling-block whereon a chandelier is hung, and that various devices have been 50 contrived for making automatic contact when a lamp-plug is placed in its socket.

I claim as new and of my invention—

The combination of the ceiling-block A, having electrical connections and cut-out fixed 55 thereto, metal shield B, removably connected to said ceiling-block, non-conducting perforated button C, supported at the base of said shield, and electric-lamp wires E, suspended 60 from said button and connected to the electrical connections on the ceiling-block, substantially as and for the purpose set forth.

HARRY M. DOUBLEDAY.
